UNITED STATES PATENT OFFICE.

HERBERT W. OWEN, OF DOVER, NEW HAMPSHIRE.

TOOL FOR APPLYING TRAVELERS TO RINGS.

1,073,280.

Specification of Letters Patent. Patented Sept. 16, 1913.

Application filed March 22, 1912. Serial No. 685,533.

To all whom it may concern:

Be it known that I, HERBERT W. OWEN, of Dover, in the county of Strafford and State of New Hampshire, have invented 5 certain new and useful Improvements in Tools for Applying Travelers to Rings, of which the following is a specification.

The travelers used in connection with the rings of spinning and twisting machines 10 are so very small and light that it is a rather delicate operation to properly locate them on the rings because it is necessary to spread them in order that they can be snapped over the top flanges of the rings. 15 The object of the present invention is to provide a tool, preferably a magazine tool, which will enable travelers to be quickly and certainly snapped onto the rings of spinning and twisting frames with little or 20 no loss of travelers.

To this end the invention consists in the tool and the magazine carrier substantially as hereinafter described and claimed.

Of the accompanying drawings,—Figure 25 1 is a side elevation of my improved tool, a spinning ring being also shown to illustrate the manner of using the tool. Fig. 2 is a plan view of the same. Fig. 3 represents a section on line 3—3 of Fig. 2. Fig. 30 4 represents a section on line 4—4 of Fig. 2, but on a larger scale. Fig. 5 is a view similar to Fig. 4, but illustrating a further step in the use of the tool, a portion of the side lug or ear being broken away. Fig. 35 6 is a detail plan of the applying end of the tool. Fig. 7 is a detail elevation of the applying end of the tool. Fig. 8 is a plan of a supplying carrier. Fig. 9 represents a section on line 9—9 of Fig. 8.

40 Similar reference characters indicate the same or similar parts in all of the views.

The body 10 of the tool is formed with an extension or tip 11 having a forwardly opening recess 12 to bear against the outer 45 edge of the top flange of a spinning ring b. Said extension is provided with a finger 13 projecting beyond the recess 12 and having a hook or lug 14 at its outer end. The rear end of the body of the tool is formed with 50 a lateral extension 15, which removably supports the magazine bar or carrier 16 having a web 17. Said bar is slightly resilient, and has a flat outer face 18 of a width equal to the thickness of the web 17, so that said bar, in transverse section, will 55 have the form or shape of the interior of a

traveler a. The web 17 is clamped between ears 15^a of the extension 15, by screws 15^b, the thickness of the web being slightly less than the space between the facing ends of the travelers so that the travelers can freely pass through the C-shaped space 15^c around the carrier 16. The forward end of the carrier 16 is curved and provided with a beveled tip 19, the convex face of this 60 curved portion having a groove 20 so that the said curved portion of the carrier, as well as the recess 12 of the tip 11, may be brought into juxtaposition with the outer edge of the top flange of the ring b, as illustrated in Figs. 1, 2, and 4.

Mounted in a longitudinal recess on the body 10 is a slide 21 having a push handle 22 at one end, said slide being normally in the position indicated in Figs. 1 and 2 by a 75 spring 23 coiled about the projecting rear end of the slide between the inner face of the handle and the rear end of the body 10. The front end of the slide is formed or provided with a head 24 which is beveled or 80 cut away to form a thin lip 25 having its extreme tip or edge curved, as best shown in Figs. 4 and 5.

In operation, and assuming that the magazine bar or carrier 16 has been supplied 85 with a number of travelers a, the user so tilts the tool that the travelers will slide to the front end of the bar 16 with one of said travelers in front of the curved front edge or pusher 25 of the thin tip of the head 24. 90 The tool is then placed in the position shown in Fig. 1, 2, and 4, the extension 13 reaching across and resting upon the top of the ring b. Then pressure on the handle so as to push the slide 21 toward the ring 95 b, causes the thin edge of the head 24 to push out the traveler a that is in front of it, the extreme edge of the head riding over the beveled tip 19 of the bar or carrier, the latter yielding sufficiently to permit this to 100 be done. As the outer edge of the top flange of the ring is in the space between the facing ends of the traveler, this pushing action of the head 24 forces the traveler from the position shown in Fig. 4 over to 105 the position shown in Fig. 5, the traveler yielding sufficiently to permit this to be done, and then contracting or snapping onto the flange of the ring b. During this operation the middle portion of the tip of the 110 pusher engages the traveler and advances it from the position shown in Fig. 4, toward

the position shown in Fig. 5, while the upper forward extension of the curved tip guides the traveler with a rocking motion so that it turns from the position where it first straddles the outer flange of the ring until it has been given substantially one-fourth rotation in its own plane, at which latter point it snaps over the inner flange of the ring, the latter position being shown in Fig. 5.

10 The hook 14 enables the tool to be used as a yarn threader as well as a traveler applier. This is due to the fact that when a traveler is to be applied to a ring, the operative places the hook 14 over the yarn and the latter is laid lightly in the groove 20 of carrier 16, so that when a traveler is then applied to the ring, the yarn as well as the top flange of the ring is inclosed by the traveler, and consequently the machine is ready to run at once without delaying to thread the traveler. The finger 13 is thicker than the tip 11 and is formed with a recess 13^a in line with the thin tip of head 24 so as to provide a side lug or ear 13^b that prevents the traveler from tipping laterally as it is being applied. In other words, the lug or ear 13^b constitutes a guide for the leading portion of the traveler that is being forced over the top of the ring by the pusher 25.

15 The magazine bar or carrier 16 is removable from the extension 15 of the body of the tool so that it may be readily loaded with a supply of travelers by such loading apparatus as illustrated and claimed in my application, Serial No. 685,532 filed concurrently herewith. A suitable stop, such as a nut 16^a removably carried by the outer end 20 of the carrier 16, is provided to prevent the travelers from sliding off from such outer end. In order that the carrier 16 may be loaded without applying it to the loading apparatus referred to, either while said carrier is connected to the tool or removed therefrom, I provide a supplemental carrier, such as indicated at 26, in Fig. 8 and 9. Said carrier may be of any length, capable of holding hundreds or thousands of 25 travelers, removable end stop nuts 27 being employed. Such supplemental carrier will be loaded by the apparatus referred to, and owing to its cross-sectional shape corresponding with the interior of the travelers 30 strung thereon, the latter can not turn in the carrier, and may be readily slid onto the carrier 16 when the nut 16^a and one of the nuts 27 are removed and the two carriers brought end to end. It is also to be understood that, if desired, a number of carriers 35 16 may be used interchangeably with one tool. All may be loaded with travelers, and when one is exhausted another may be substituted therefor.

40 65 The bar or carrier 16, as has been de-

scribed, is of such shape transversely as to fit the interior of the string or series of travelers to prevent the travelers from rotating so as to get out of proper position for application to the ring. The carrier 26 70 is of similar shape in cross section. Of course, if the travelers to be used in connection with the tool are of different shape from that illustrated, then the bar or carrier 16 would be correspondingly shaped in 75 transverse section.

The recess 12 formed in the extension member of the body steadies the tool by engagement with the flange of the spinning ring and the slide 21 and the head 24, 80 particularly the extreme tip having the curved front edge, constitutes a pusher which is movable toward the spinning ring so that as the travelers are supplied one by one in front of the pusher and the latter 85 projected as has been described, the travelers may be quickly applied wherever needed.

The beveled tip 19 of the carrier 16 provides a throat or space between it and the adjacent side face of the recessed tip 11, 90 which is not wide enough to permit a traveler to escape through it, but which can be spread or made wider by the crowding action of a traveler that is being pushed through such space by the thin lip 25. The 95 driving edge of the lip 25 is not at a right angle to the path of movement of the pusher, but is irregular so that after the lower point of the traveler has been inserted under the ring flange a continued movement of the pusher and its irregular tip will turn or rotate the traveler in its own plane and spring it over the top of the ring, the width of which is always greater than the space between the points of the traveler. 100 105

I claim:

1. An implement for applying travelers to spinning rings, comprising a body having a tip recessed to engage the flange of a ring, a carrier to supply travelers one by 110 one adjacent the recess of the tip, the delivering end of the carrier being yieldable away from said tip, and a pusher movable between said delivering end and the recessed tip to spring the traveler adjacent 115 the tip over the top of the ring.

2. An implement for applying travelers to spinning rings, comprising a recessed member to engage the flange of a ring, a pusher movable alongside said member, and a carrier for supplying ring travelers one by one in front of said pusher, said carrier comprising a round rod having a flattened side.

3. An implement for applying travelers to spinning rings, comprising a body having a tip recessed to engage the flange of a ring, a carrier to supply travelers one by one adjacent the recess of the tip, said carrier comprising a round rod cut away to 125 130

- receive the in-turned points of the travelers and having a web, the implement having a clamp to hold said web, and a pusher for springing the tip over the top of the ring.
- 5 4. An implement for applying travelers to spinning rings, comprising a body having a tip recessed to engage the flange of a ring, a carrier having a beveled end adjacent the side of the recessed tip, and a 10 pusher movable between the said beveled end and the side of the tip.
5. A tool of the character described, comprising a recessed member to engage the flange of a ring, a pusher movable alongside said member, and a magazine carrier having a beveled tip in proximity to said recessed member, and having a groove in its front face adapted to engage the flange of the ring.
- 15 20 6. A tool of the character described, comprising a body having an extension formed

with a forwardly opening recess, and having a finger projecting beyond said recess, a slide having a curved pushing tip movable alongside of said finger, and a magazine 25 carrier having a beveled tip adapted to deliver travelers one by one in front of said pushing tip.

7. A magazine carrier for a tool of the character described, said carrier comprising 30 a single bar capable of alone holding spinning ring travelers, said bar having longitudinal guiding surfaces for the in-turned ends of spinning ring travelers, the bar also having means for preventing accidental end- 35 wise removal of ring travelers therefrom.

In testimony whereof I have affixed my signature, in presence of two witnesses.
